US0D1064690S

(12) **United States Design Patent** (10) **Patent No.:** **US D1,064,690 S**
(45) **Date of Patent:** **** Mar. 4, 2025**

(54) **HANDLE**

(71) Applicant: **Gasser Chair Co., Inc.**, Youngstown, OH (US)

(72) Inventor: **Greg Gasser**, Youngstown, OH (US)

(73) Assignee: **Gasser Chair Co., Inc.**, Youngstown, OH (US)

(**) Term: **15 Years**

(21) Appl. No.: **29/913,315**

(22) Filed: **Sep. 29, 2023**

(51) LOC (15) Cl. **06-06**

(52) U.S. Cl.

USPC **D6/702**; D8/16

(58) **Field of Classification Search**

USPC D8/300, 301, 303, 307, 313, 315-320

CPC E05B 1/00; E05B 1/0015; A47B 95/02;
A47B 2095/024

See application file for complete search history.

Primary Examiner — Calvin E Vansant

Assistant Examiner — Benjamin L. Gray

(74) *Attorney, Agent, or Firm* — Sand, Sebolt & Wernow Co., LPA

(57) **CLAIM**

The ornamental design for a handle as shown and described.

DESCRIPTION

FIG. 1 is a rear, top, left side isometric perspective view of a handle in accordance with my design;

FIG. 2 is a front, top, left side isometric perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines shown in the drawings represent portions of the handle that form no part of the claimed design.

1 Claim, 4 Drawing Sheets
